UNITED STATES PATENT OFFICE.

JOHN H. GOSS AND EDWARD L. WOLFF, OF WATERBURY, CONNECTICUT, ASSIGNEES
TO SCOVILL MANUFACTURING COMPANY, A CORPORATION OF CONNECTICUT.

CASTING APPARATUS.

Application filed March 6, 1917. Serial No. 152,536.

To all whom it may concern:

Be it known that we, JOHN H. GOSS and EDWARD L. WOLFF, citizens of the United States, residing at Waterbury, county of New Haven, and State of Connecticut, have invented certain new and useful Improvements in Casting Apparatus, fully described and represented in the following specification and the accompanying drawings, forming a part of the same.

This invention relates to apparatus for casting metal.

Hand pouring of the molten material in metal casting oftentimes results in defects and imperfections which impair or destroy the workable quality of the product. Devices have been devised for non-manual pouring, but such devices as heretofore known have been subject to certain objections and disadvantages. For example, they have been found difficult to work with because of lack of protection to the operators; it has been found difficult to attain and retain proper alignment between the molds and pouring members; they have lacked means whereby the molds could be properly and readily cleaned; and, due to these and other causes, their operation has been so clumsy, slow and ineffectual, that they have not attained the proper commercial standard of success.

It is the principal object of this invention to provide apparatus for casting metal which eliminates the objectionable disadvantages of hand pouring and of the casting devices as heretofore known, such as those mentioned, and which makes it possible to obtain a product satisfying the demands of commercial requirements.

With this general object in view, the invention consists in the combinations, details of construction and arrangements of parts which will first be described in connection with the accompanying drawings and then more particularly pointed out.

In the drawings—

Figure 1 is a front elevation of casting apparatus constructed in accordance with the invention;

Figure 2 is a side elevation of the same, in position for melting;

Figure 3 is a top plan view of the apparatus as shown in Fig. 2;

Figure 4 is a similar view, the mold being in position for cleaning and the like, subsequent to casting;

Figure 5 is a vertical cross-sectional view (enlarged) of the furnace and parts associated therewith;

Figure 6 is a view similar to Fig. 3, illustrating a modified form of mold sections, and

Figure 7 is a view similar to Fig. 4, showing the same modified form of mold sections as shown in Fig. 6.

In the apparatus illustrated the molds are formed by a plurality of mold sections and the invention in its entirety includes means whereby the mold sections may be movable and the crucible tiltable for pouring without the risk of the loss of proper alignment between the parts. While this may be accomplished by various constructions, in the exemplification shown, the apparatus includes a supporting frame which comprises upright standards 25, cross-braces 26 and side arms 27. This supporting frame is a unitary structure, as, for example, a single casting, and carries, as hereinafter described, the tilting crucible and the folding mold sections. By the use of such a unitary support for both crucible and molds, the proper alignment is retained between molds and crucible, and a large number of successive pourings can be made without repair or adjustment of the parts and the like.

There is provided a crucible tiltable for pouring. Although capable of a wide range of constructions, in the form shown a crucible 28 is carried by a furnace 29. This latter comprises a plurality of superposed rings 30 covered with an outer shell 31 and lined with fire brick 32. It has also a bottom plate 33 in which there is a hinged door 34. In the bottom of the furnace are blocks 35 on which the crucible rests so as to extend somewhat above the top of the furnace, as shown in Fig. 5. It will be seen that there is an annular space 36 between the crucible and the furnace wall through which passes the heating medium as hereinafter described.

There is provided a removable hood for covering the crucible and furnace, and in effect serving as an extension thereof, during the melting of the charge. While such a hood may be of various constructions, that illustrated comprises a central cylindrical portion of superposed rings 37 covered by an outer shell 38 and carrying at the bottom two rings 39, 40 having mutually engaging shoulders, as shown in Fig. 5. The ring 40 is provided with concentric gaskets 41 which contact with the top of the furnace when the hood is in place to effect a proper seal between the parts. The hood carries a cylindrical crucible-extension 42 which roughly aligns with the crucible proper and which has an upper shoulder 43 engaged by one of the rings of the hood wall to carry the member 42 when the hood is raised. Above the central section of the hood is an annular cover 44 having an insertion of fire brick 45 and carrying an annular throat member 46 by mutually-engaging shoulders, as clearly appears in Fig. 5. To close the furnace opening, on top of this annular cover is a removable lid 47 faced with fire brick 48 and carried by a supporting bracket 49 pivoted on a pin 50 and having an operating handle 51. By manipulating the handle 51, the lid is displaced to expose the cover opening and permit charging of the crucible, inspection of the charge and the like.

The hood is provided with trunnions 52 to receive a bail carried by a crane or the like (not shown) whereby the hood is lifted off and away from the furnace, when the charge is ready for pouring.

Means is provided for tilting the crucible to pour the charge. While capable of a wide range of constructions, in the embodiment shown, the furnace is pivoted to the main supporting frame as at 53. To tilt the furnace, pivoted to the side thereof, as at 54, is a connecting rod 55 fastened to a piston rod 56 the piston 57 of which operates in an air cylinder 58. This cylinder has a base 59 pivotally carried by a large bracket 60 on the main frame, this base 59 having an air passage 61 extending laterally through the pivot 50 of the base (Fig. 2) and arranged to be connected with any suitable source of air under pressure. The action of the piston-operated connecting rod tilts the furnace about its pivotal connections, to permit the crucible to pour.

The furnace here shown as an example has at one side, near the bottom, a large square heat-admission flue 62 (Figs. 1 and 2), and near the top of the other side, the furnace has an exit flue 63. The opening of the admission flue is arranged to register with a fuel burner (not shown) which may be of any suitable construction. The heating medium from the burner passes into the flue 62 and

up through the furnace and hood about the crucible and out via the exit flue 63, which may be connected up as desired. In a preferred plant layout the furnaces are alternately right and left handed to permit two adjacent furnaces to have common burners and common escape flues. These furnaces are identical in construction, except that the position of the various parts is reversed, as shown in the drawings. Thus, Fig. 3 shows a left hand and Fig. 4 a right hand furnace, and when two such furnaces are adjacent, the burners above mentioned may be located between them. To the right of the furnace of Fig. 4 will be another left hand furnace and between them will be a common outlet flue, into which the two exit flues 63 can discharge.

There is provided means for covering the annular space surrounding the crucible when the hood is removed, to protect the workmen from the hot gases and to protect the furnace from bits of the charge which may splash out of the crucible. Although capable of a wide range of constructions, in the embodiment shown, pivoted to the furnace, as at 64, is a shield 65 which is incompletely annular. This shield has two wings 66 making the top plan roughly inverted U-shaped, the hinge being at the ends of the U. When the hood is in place during melting of the charge, this shield is swung up into a nearly vertical position, as shown in Figs. 1, 2 and 5, so as to be out of the way. When, however, the hood is removed, the shield is swung down, as shown in Fig. 4, to cover the annular space between the crucible and the furnace wall.

There is provided means to permit pouring with this shield in place and also means for supporting the crucible in its tilted position, as during pouring. Although these ends may be attained by various constructions, in the embodiment shown, there is provided a member in the form of a spout 65^a. It has been mentioned that the shield comprised an incomplete annulus (Fig. 1). At the opening, the edges are substantially parallel, as appears in Figs. 1 and 4, and these edges form a track for the spout 65^a which is carried thereby. By this construction, the member 65^a both serves as a spout and completes the shield so that the entire annular open space is covered. This spout member 65^a also serves as a support for the crucible while in a tilted position as for pouring. To bring spout and crucible into proper relation, the spout is made to conform with the crucible and the spout is clamped against the side of the crucible when the shield is in place, means being provided for adjusting the position of the spout. Although capable of various constructions, in the form shown the spout is slidably in its bearing track. Pinned to the spout by bolt 65^b is an

adjusting lever 67 fulcrumed as at 68 and having a slotted arm 69 riding over a pin 70 on the shield wing. Extending out from the lever is an operating handle 71. By manipulation of this handle the spout 65^a is moved in and out in its track so that it may be properly adjusted to clamp against the crucible and support it while tilted.

There is provided means whereby the molds are carried by the main supporting frame in such manner that they can be readily placed in a position to be accessible for cleaning and the like. While capable of a wide range of constructions, in the exemplification shown the molds are formed by a plurality of vertical mold sections 72, the back of one section serving as the face or cover of the next mold. These molds are carried by a swinging bracket 73. Each mold section has near the top and bottom an arm 74 at the end of which is a socket 75 pivotally mounted on a pintle 76 carried by the bracket. It will be observed from Figs. 3 and 4, that these arms are of different lengths. As a result, when the molds are opened, complete and ready access is obtained to the individual sections. The bracket itself is pivotally connected to the frame. As here shown as an example, near the top of the bracket, at one side, is a bifurcated pintle socket 77 by which the bracket is mounted on a pin 78 which passes through a supporting arm 79 extending out from the main supporting frame. At the bottom of the bracket is a gudgeon 80 mounted on a pintle 81 passing through a similar arm 82 of the main frame, and at an intermediate point is a second bifurcated pintle socket 83, pintle 84 and supporting arm 85.

When the molds are closed for pouring, as in Fig. 3, it will be seen that they are in such position that the back of one covers the next, the last one to the left (in the drawing) being open and so not receiving any charge. After casting, the bracket is swung out on its hinges, thus swinging all the mold sections away from pouring position, and, further, the individual sections are swung out on their pintles until they take some such position as that shown in Fig. 4. Ready access to each mold for cleaning and the like is thus obtained.

There is provided means for positively and yieldingly locking the mold sections together for pouring. This may be accomplished in numerous ways. In the construction shown, pivoted to the frame, as at 86, is a plurality of clamping arms 87, there being one for each of the side frame arms. These clamping arms carry triangular clamping blocks 88 pivoted thereto and having a straight face to contact with the end mold section. Straddling the ends of the side frame arms and pivoted thereto,

are levers 89 which in turn are straddled by and have pivoted thereto the forked ends 90 of locking bars 91. The other ends of the locking bars have eyes 92, the intermediate portions being formed as turn-buckles 93. When the molds are closed, the clamping arms 87 are swung in, with the members 88 bearing against the last mold section so as to properly distribute the clamping pressure. The locking eyes 92 of the locking bars 91 are hooked over the ends of the clamping bars 87, which may have notches to receive said eyes. This positively locks or clamps the mold sections together, but due to the construction of the locking parts, there is enough inherent resiliency to take care of the slight expansion of the mold sections. If adjustment of the tension is desired, it is attained by manipulation of the turn buckles 93.

To release the molds for opening, the levers 89 (which are provided with sockets 94 to receive a crowbar or similar instrument) are manipulated to swing the locking bars 91 from engagement with the clamping arms 87 and both arms and bars are swung out of the way, as, in Fig. 4, to permit the mold sections to be unfolded, as before described.

Above the molds, in the present embodiment, is placed a receptacle or strainer 95, Figs. 1 and 2, for receiving the charge from the spout, this strainer having openings to distribute the metal to the respective molds.

There is provided means whereby a floor or platform is provided in relatively close proximity to the bottom of the mold sections for catching the castings when the molds are opened. It has been stated elsewhere that the apparatus of the present invention is adapted to casting bars and the like of various lengths. To prevent the castings, particularly in the case where the molds used are quite short, from dropping any great distance when the molds are opened, a platform is provided, such that it may be adjusted with relation to the particular mold length used. Although such an adjustable platform is capable of various constructions, in apparatus embodying

the invention to the best advantage, it is in the form of a large tray which may be placed in a number of positions on the frame of the apparatus. For example, in the embodiment illustrated, there is provided a flat tray 96 of the configuration shown in Fig. 4. This tray has at one side an outwardly extending lug 97 which rests on the side bars of the frame and a plurality of hooks 98 at the rear which hook over any one of the rear cross bars of the frame of the apparatus as shown in Fig. 2. From this figure it will be seen that the platform or tray 96 is in relatively close proximity to the bottom of the molds, so that when

the molds are opened, the castings will have but a short distance to drop. When shorter or longer molds are used, the platform or tray is removed and replaced on cross bars 5 higher or lower on the frame, as the case may be.

To recapitulate the operation, assuming the hood is in place, the shield being swung into its out-of-the-way position and the crucible charged, the heating medium enters via the admission flue and passes up around the crucible and out via the exit flue. If open, the mold sections and the bracket 73 are swung around to pouring position (Fig. 3) 10 and are clamped or locked firmly together by hooking the eyes of the locking bars 91 over the ends of the clamping arms 87. When the charge is ready for pouring, a crane carrying a bail is advanced and the 15 hood is attached and bodily removed. Thereupon the shield 65 is swung down into its protecting position and the spout 65^a is slid up until it is clamped against the crucible, so as to complete 20 the shield and be in supporting position when the crucible is tilted. Air being admitted to the cylinder 58 the furnace is tilted by the connecting rod 55 and the molten metal is poured down the spout into 25 the strainer 95 and so into the molds. When the pouring is completed the air is cut off and the furnace returned to normal position. When the metal in the molds has properly hardened, the locking bars are disengaged 30 from the clamping arms and both bars and arms swung out to the position shown in Fig. 4, whereupon the molds are unfolded sufficiently to permit of removal of the castings. For cleaning and the like the swinging 35 bracket is swung out to carry the molds away from the machine and the sections are separated, as shown in Fig. 4. The shield is then swung back, the hood moved into place again, and the apparatus is ready for the 40 next charge.

Figs. 6 and 7 illustrate a modification of the invention adapted for casting billets rather than flat bars or slabs. In this case only one article is cast at a time. To this end there are two mold sections 100, each having a semi-cylindrical mold opening. Secured to the upper and lower end of each section are arms 101 having sockets mounted on pintles 102 carried by a swinging bracket 55 103 which is similar to the swinging bracket already described though slightly different in shape. Otherwise this construction is like that already described.

It is noted that this apparatus is adaptable for molds of a wide range of lengths, from relatively short ones to molds substantially commensurate with the distance between the uppermost and lowermost side frame arms 27. In the present instance the 60 molds are of an intermediate length. If

longer bars or billets are desired, the mold sections are correspondingly changed as is also the swinging bracket and the tray 96, the apparatus as a whole, however, being unchanged.

What is claimed is:

1. In a metal casting apparatus, and in combination, a supporting framework including an upright support and side arms extending therefrom, a crucible furnace pivotally carried by said framework, a bracket pivotally mounted on said side arms, and a plurality of mold sections pivotally mounted on said bracket.

2. In a metal casting apparatus, and in combination, a supporting framework including an upright support and two sets of side arms extending therefrom, a crucible furnace pivotally carried by said framework, a bracket pivotally mounted on one set of side arms, a plurality of mold sections pivotally mounted on the bracket, and mold-locking elements carried by the other set of side arms.

3. In metal casting apparatus, and in combination a support, a mold carried thereby, a crucible, a furnace carrying said crucible and pivotally carried by said support, and means for tilting said furnace to pour the charge into said mold.

4. In metal casting apparatus, and in combination a support, a plurality of movable mold sections carried thereby, a crucible, a furnace carrying said crucible and pivotally carried by said support, and means for tilting said furnace to pour the charge into the mold or molds formed by said sections.

5. In metal casting apparatus, and in combination a support, a swinging bracket pivotally carried thereby, a plurality of mold sections pivoted to said bracket, a crucible, a furnace carrying said crucible and pivotally carried by said support, and means for tilting said furnace to pour the charge into the mold or molds formed by said sections.

6. In metal casting apparatus, and in combination a tilting furnace, a crucible within said furnace, a removable hood for the furnace, a shield for covering the space between the crucible and the furnace wall, and a spout forming part of said shield.

7. In metal casting apparatus, and in combination a furnace, a crucible within said furnace, a removable hood for the furnace, and a shield carried by the apparatus and movable into a position to cover the space between the crucible and the furnace wall when the hood is removed and out of the way when the hood is in place.

8. In metal casting apparatus, and in combination a furnace, a crucible within said furnace, a removable hood for the furnace, and a shield pivotally carried by the furnace for covering the space between the

- crucible and the furnace wall when the hood is removed.
9. In metal casting apparatus, and in combination a tilttable furnace, a crucible within said furnace, a removable hood for the furnace, a shield pivotally carried by the furnace for covering the space between the crucible and the furnace wall when the hood is removed, and a spout forming part of said shield. 70
10. In metal casting apparatus, and in combination a furnace, a crucible within said furnace, a removable hood for the furnace, a shield for covering the space between the crucible and the furnace wall when the hood is removed, and an adjustable spout carried by said shield and movable to abut against the crucible. 75
11. In metal casting apparatus, and in combination a furnace, a crucible within said furnace, a removable hood for the furnace, a shield for partially covering the space between the crucible and the furnace wall when the hood is removed, and a spout carried by said shield to cover the space not covered by the latter, the position of said spout being adjustable. 80
12. In metal casting apparatus, and in combination a furnace, a crucible within said furnace, a removable hood for the furnace, an incomplete shield for covering the space between the crucible and the furnace wall when the hood is removed, a spout carried by said shield and completing the same and slidable to abut against the crucible, and means for moving said spout. 85
13. In metal casting apparatus, and in combination a support, a bracket pivotally carried by said support, and a plurality of cooperating mold sections pivotally secured to said bracket. 90
14. In metal casting apparatus, and in combination a support, a plurality of cooperating mold sections connected with said support so as to be movable in unison and individually separable, and a crucible also carried by said support and movable for pouring. 95
15. In metal casting apparatus, and in combination a support, three or more open faced mold sections secured to said support to form complete molds and separable to provide ready access to the interior of the individual sections. 100
16. In metal casting apparatus, and in combination a support, a plurality of mold sections pivotally carried by said support, the distance from the molds to their respective pivotal points being unequal. 105
17. In metal casting apparatus, and in combination a movable bracket, a plurality of mold sections, each section having a supporting arm pivoted to said bracket, said arms being of unequal length. 110
18. In metal casting apparatus, and in combination a plurality of separable mold sections, a stationary member, a plurality of movable members and means for clamping the molds between said stationary member and said movable members. 115
19. In metal casting apparatus, and in combination a plurality of separable mold sections, a stationary member, a plurality of movable clamping arms, means for clamping the mold sections between said stationary member and said arms, and mold engaging blocks pivotally carried by said clamping arms. 120
20. In metal casting apparatus, and in combination a plurality of separable mold sections, a stationary member, a plurality of swinging clamping arms, a plurality of swinging locking links for clamping the mold sections between said stationary member and said arms, and means for adjusting the length of said links. 125
21. In metal casting apparatus, and in combination a tilttable furnace, a crucible within said furnace, a removable hood for the furnace, a shield for covering the space between the crucible and the furnace wall when the hood is removed, and a spout associated with the shield and movable to abut against the crucible to support the same when in tilted position. 130
22. In metal casting apparatus, and in combination a tilttable furnace, a crucible within said furnace, a removable hood for the furnace, a shielding member for partially covering the space between the crucible and the furnace wall when the hood is removed, and a spout carried by said shielding member to cover the space not covered by the latter, and movable to abut against the crucible to support the same when in tilted position. 135
23. In metal casting apparatus, and in combination a support adapted to carry mold sections of different lengths, a platform, and cooperating parts on the support and platform respectively, whereby the platform may be located on the support in a plurality of positions for catching the articles cast. 140
24. In metal casting apparatus, and in combination a support adapted to carry mold sections of different lengths, and a platform for catching articles cast and adapted to be carried by said support in a plurality of positions. 145
25. In metal casting apparatus, and in combination a support comprising a plurality of cross pieces and adapted to carry mold sections of different lengths, a platform, and means associated therewith for cooperating with any of said cross pieces to carry said platform in a position to catch the articles cast. 150
26. In metal casting apparatus, and in combination a support, a plurality of molds 130

- carried thereby, and a receptacle for receiving the charge and distributing it to said molds.
27. In metal casting apparatus, and in combination a support, a plurality of molds carried by said support, a crucible movable to pour the charge, and a receptacle for receiving the charge from the crucible and distributing it to said molds.
- 10 28. In metal casting apparatus, and in combination a support, a plurality of movable mold sections carried by said support to form a plurality of molds, a crucible movable to pour the charge, and a receptacle for receiving the charge from the crucible and distributing it to said molds.
- 15 29. In metal casting apparatus, and in combination, a support, a plurality of separable mold sections carried by the support, a clamping bar for locking the mold sections together pivotally associated with said support and movable on its pivot to span the mold sections, and a lever for manipulating said clamping bar.
- 20 30. In metal casting apparatus, and in combination a plurality of separable mold sections, a clamping bar mounted to span the mold section for locking said mold sections together, and a lever pivoted to said bar for manipulating the same.
- 25 31. In metal casting apparatus, and in combination a furnace, a crucible within said furnace, a shield for covering the space between the crucible and the furnace wall, and a spout forming part of said shield.
- 30 32. In metal casting apparatus, and in combination a furnace, a crucible within said furnace, a shield for covering the space between the crucible and the furnace wall, and an adjustable spout carried by said shield and movable to abut against the crucible.
- 35 33. In metal casting apparatus, and in combination a furnace, a crucible within said furnace, an incompletely annular shield for covering the space between the crucible and the furnace wall, a spout in sliding relation with the shield for completing the same, and an adjusting lever pivoted to the shield and having an operating connection with the spout, for sliding the spout toward and away from the crucible.
- 40 34. In a metal casting apparatus, and in combination, a supporting framework including an upright support and two sets of side arms extending from one side thereof, a tilting crucible carried by said supporting framework, a bracket pivotally mounted on one set of side arms, a plurality of separable mold sections carried by said bracket, a plurality of mold clamping elements pivotally mounted on said framework opposite the second set of said side arms, and mold-locking elements carried by said last named side arms and having portions for engaging said clamping elements.
- 45 50 55 60 65
- In testimony whereof, we have hereunto set our hands.
